United States Patent Office

Des. 182,773
Patented May 13, 1958

182,773

FINGER RING SPIRIT LEVEL

Edward W. Souter, Moss Beach, Calif.

Application September 20, 1957, Serial No. 47,790

Term of patent 14 years

(Cl. D45—10)

Fig. 2.

Fig. 3.

Fig. 4.

Fig. 5.

Fig. 6.

Fig. 1 is a perspective view of a finger ring spirit level embodying my new design;

Fig. 2 is a top plan view of the same;

Fig. 3 is a front elevation view of the same;

Fig. 4 is a side elevation of the same;

Fig. 5 is a rear elevation of the same; and

Fig. 6 is a bottom view of the same.

I claim:

The ornamental design for a finger ring spirit level, substantially as shown.
